Filed May 22, 1970, Ser. No. 23,105

Term of patent 14 years

Int. Cl. D26—06; D29—02

U.S. Cl. D48—32

FIG. 1 is a perspective view of a vehicle safety light and bracket therefor showing my new design;

FIG. 2 is a side elevational view of the combined vehicle safety light and bracket therefor on a slightly reduced scale;

FIG. 3 is an end elevational view thereof;

FIG. 4 is an elevational view of the side opposite that shown in FIG. 2;

FIG. 5 is an elevational view of the end opposite that shown in FIG. 3;

FIG. 6 is a top plan view thereof; and

FIG. 7 is a bottom plan view thereof.

The interior concentric ring faceting of the lenses is omitted in FIGS. 3, 5, 6 and 7 for convenience of illustration.

I claim:

The ornamental design for a vehicle safety light and bracket therefor, substantially as shown and described.
